United States Patent Office

Des. 217,650
Patented May 19, 1970

217,650

FROZEN BEVERAGE DISPENSING MACHINE OR SIMILAR ARTICLE

Clark L. Lofgren, Golden Valley, Minn., assignor to The
Cornelius Company, Anoka, Minn., a corporation of
Minnesota

Filed Dec. 3, 1968, Ser. No. 14,762

Term of patent 14 years

Int. Cl. D15—12

U.S. Cl. D94—3

FIG. 1 is a perspective view showing the front and one side of a frozen beverage dispensing machine showing my design, the opposite side having a similar appearance.

FIG. 2 is a perspective view showing the rear and said one side thereof.

FIG. 3 is a top view thereof.

I claim:

The ornamental design for a frozen beverage dispensing machine or similar article, substantially as shown and described.
